INVENTOR.

William S. Blunt, by A. S. Newell, Esq., Atty.

UNITED STATES PATENT OFFICE

WILLIAM S. BLUNT, OF BAY RIDGE, NEW YORK, ASSIGNOR TO KATE S. BLUNT, OF SAME PLACE.

IMPROVEMENT IN PUMPS.

Specification forming part of Letters Patent No. 222,374, dated December 9, 1879; application filed September 24, 1879.

To all whom it may concern:

Be it known that I, WILLIAM S. BLUNT, of Bay Ridge, Kings county, New York, have invented, made, and applied to use Improvements in the Construction of Pumps; and I do hereby declare that the following is a full, clear, and correct description of the same, reference being had to the accompanying drawings, making part of this specification, and to the letters of reference marked thereon, in which—

Figure 1 is a side elevation of my improved pump. Fig. 2 is a vertical section of the same. Fig. 3 is a top view of my improved pump. Fig. 4 is a top view of the bisected collars or rings employed; Fig. 5, an end view of the bisected collars or rings. Fig. 6 is a view of the pump-head detached from its resting-place upon the air-chamber, showing the handle at its extreme elevation and crank depressed, so as to project below the opening of the pump-head, when it rests or is rotated upon the top of the air-chamber, for convenience in attaching or detaching the pump-rod to or from the crank.

In the drawings like parts of the invention are designated by the same letters of reference.

The nature of the present invention consists in improvements as more fully hereinafter described, and will be found to relate to the combination of a revolving pump-head provided with a rock-shaft and nozzle with an air-chamber and pump-barrel, the object of the invention being economy of manufacture, increased efficiency of the air-chamber, and the ability to pass a direct stream of water through the entire pump and out of the nozzle of the revolving pump-head.

To enable those skilled in the arts to make and use my invention, I will describe its construction and operation.

A shows a pump-barrel provided with a spout, B, and air-chamber C. The upper portion of the air-chamber C is continued in its manufacture, as at e, forming a base or support for the bisected collar-clamps, and also for the elastic packing.

D shows the pump-head, which should be made water-tight, and which is provided at its

top with the spout E, in line with the vertical axis of the pump-barrel A. Within this head D, upon one side of the same, is inserted a rock-shaft, F, to which is attached a crank, f, connected at its lower end to the upper end of the pump-rod g by means of a cross-bolt, pin, or any suitable mechanical device for the purpose. G is the pump-handle, pinned upon the projecting end of the rock-shaft F.

H is a packing of rubber or suitable material, placed directly below the base of the pump-head; and I are bisected collar-clamps, by which the head is retained in its position upon the continued portion of the air-chamber. These collar-clamps consist of plates of metal, which, when brought together, form a square with circular opening, as clearly shown in Figs. 4 and 5 of the drawings. These plates have a portion of their under side excavated, within which the lower circular portion of the pump-head is received and rests; and one of these plates has a portion of its ends cut away to receive the corresponding projecting ears of the other plate when the plates are brought together into position upon the continued portion of the air-chamber. These clamps, after being placed in position, are secured therein by means of screws passed through them and into the continued portion of the air-chamber.

J is the plunger, connected to the lower end of the rod.

Such being the construction, it will be observed that the head may be revolved, so as to bring the handle into any desired position relative to the spout upon the barrel; that by closing the lower spout by means of cocks, valves, or screw-caps a direct water-way is afforded through the entire pump to the spout in the upper portion of the pump-head, and that by closing this spout in like manner the lower spout is availed of for the exit of the water. Thus the pump may be used to pump water into a tank through the upper spout, while the lower spout is more directly intended for drawing water or for use in connection with hose.

The efficiency of the air-chamber is increased, as the pump-works heretofore contained in it are placed above it and independent of it, and, from its position directly upon the barrel

and between it and the water-tight head, the tendency of air to leak from the same is lessened.

Economy of manufacture is attained, as the pump-head is more easily rendered water-tight than air-tight, and the motive power by which the rod and plunger are operated are expeditiously connected by bringing the head into the position shown in Fig. 6 of the drawings, and then connecting the crank upon the rock-shaft with the upper end of the pump-rod.

The air-chamber, placed as shown, cannot become exhausted save by absorption under heavy and continuous pressure of water, and can then be easily supplied with air by water being allowed to waste itself from the lower

spout, when air will, of course, take its place in the air-chamber.

Having now set forth my invention, what I claim as new is—

In pumps, the combination of the following elements: a pump-barrel provided with a spout and supporting an air-chamber, and a revolving head provided with a spout and containing a rock-shaft, to which is attached a handle, and a crank connected to the pump-rod, constructed and operating substantially as and for the purposes specified.

WILLIAM S. BLUNT.

In presence of—

WILLIAM V. H. HICKS,
A. SIDNEY DOANE.
